DOUGLAS R. BROWN, OF COFFEYVILLE, KANSAS, ASSIGNOR TO THE OIL COUNTRY SPECIALTIES MFG. CO., OF COFFEYVILLE, KANSAS, A CORPORATION OF KANSAS

POWER UNIT FOR OIL WELLS

Application filed November 30, 1927. Serial No. 236,637.

This invention pertains to power units, such as particularly adapted for driving deep wells, such as oil wells.

The power unit for a deep well, such as an oil well, must be capable of handling efficiently a number of distinctly different kinds of operations. Once the drilling of the well has been completed and the pumping operations begun, there are several different operations incident to the handling of the well, which includes besides the pumping operation the pulling out or inserting of pump rods or pump tubes and the like. When the well is pumping, there is a considerable length of pump rod suspended from one end of the walking beam which must be raised and lowered continually during the pumping operation. In most cases the weight of this rod is counter-balanced by a corresponding weight hung on the other end of the walking beam. In many cases, however, such counter-balancing is not accurate, and there is still a considerable weight of pump rod which is unbalanced and which must be started and stopped at each end of each stroke. This puts an intermittent load on the power unit which drives the pump. As the pumping is usually carried out by means of an electric motor as a drive, such intermittent load works the motor at a poor efficiency and puts unnecessary strains upon the driving connections.

One of the objects of this invention, therefore, is to provide a driving unit which is self-contained and by means of which the fluctuations of load on the driving motor may be reduced to a minimum.

In order to balance the intermittent pumping load, a flywheel is included in the make-up of the power unit so as to reduce the fluctuations. During the operation of extracting or inserting pump rods, the motor is used as a hoist motor. This service requires rapid starting, quick acceleration and quick stopping. A flywheel included in the make-up of the power unit would be a distinct disadvantage during this kind of service. It would retard the starting so as to require a longer time for lifting a given section of pump rod, and when the time comes

for stopping, it would provide an increased momentum which would have to be overcome in stopping. In order to effect a quick stop during these operations, it is customary to reverse the motor. It will easily be seen that a flywheel would add to the load which the motor must stop under these conditions and might cause the motor to burn out.

Another object of this invention, therefore, is to provide a power unit which while being capable of reducing the fluctuations of a pumping load, may be converted to a flexible drive which is adapted to the lifting or rod pulling operations required at the well.

Another object is to provide a power unit of substantial construction which will reduce the speed of the motor to a speed adapted for driving the well rig and which will be self-contained and easily applied to any well installation.

Another object is to provide a power unit having a flywheel incorporated therein by which power fluctuations will be reduced to a minimum and which flywheel is disconnectible so that its effects may be eliminated.

Further objects will appear from the following description, taken in connection with the accompanying drawing, in which—

Figure 1 is a side view of an oil well rig, showing the application of a power unit embodying this invention;

Figure 2 is a section on line 2—2 of Figure 1; and

Figure 3 is a section on line 3—3 of Figure 2.

Referring to the drawing, Figure 1 shows an oil well rig of standard construction including a derrick 1 which is placed over the well 2 in the usual manner and is provided with a hoisting cable 3 wound on a reel 4 driven by a belt 5 from a drive shaft 6, which in turn is driven by a band wheel 7 connected by a belt 8 to the power unit shown at the left-hand side of Figure 1. The shaft 6 also drives by means of a crank 9 a walking beam 10, to the end of which the pump rod 11 is attached during the pumping operations. The weight of the rod may be balanced by a counter-weight 12 hung on the other end of the beam 10. These parts may all be of any

standard construction usual in wells of this type and need not be described in detail since they are familiar to all those skilled in the art.

- 5 During the operation of extracting the
pump rods, said rods are disconnected from
the beam 10 and hung on the end of the cable
3, and the rods are then lifted by operating
the reel 4. This is a simple hoisting opera-
10 tion. Since the rods are lifted in sections
(about fifty or sixty feet of rod being lifted
at one operation, disconnected from the re-
maining rods and lowered to the ground,
15 after which the cable is attached to the next
section, which is lifted in a similar way) this
service involves a succession of hoisting op-
erations in which the motor is started,
stopped and reversed quite frequently.
19 During the pumping operation, the rods 11
20 are attached to the walking beam, as shown,
and the motor runs continuously so as to re-
ciprocate the rod in the well to pump the oil.
Such operation may be continuous for from
twelve to twenty-four hours a day.
25 Referring more particularly to Figures 2
and 3, 13 designates a base which may be of
cast iron or other suitable material adapted
for mounting on a foundation 14 of concrete
or other similar material. The base 13 is
30 constructed to provide a platform 15 upon
which an electric motor 16 may be mounted.
The base itself may be adjustably mounted
upon rails 17 so that it may be moved back
and forth to adjust the belt tension. The
35 base 13 is provided with a chamber 18 pro-
vided at its ends with bearings 19 in which
is journaled a countershaft 20. The bear-
ings 19 are shown as roller bearings, but any
other suitable type may be employed. The
40 chamber is closed at its ends by caps 21 so
that it may be filled with oil or similar lubri-
cant if desired. A pipe 22 communicating
with the chamber 18 leads to the outside of
45 the base 13 and is provided at its end with
a fitting 23 by means of which oil may be in-
serted or withdrawn from the chamber.

50 Suitably keyed to the end of the shaft 20 is a sprocket 24 connected by a chain 25 to a similar sprocket mounted on a shaft 26 of the motor 16. By means of these connections, the shaft 20 is driven by the motor 16. The sprocket 24 and the chain 25 are enclosed in a suitable housing 27 which may also be adapted for containing oil to lubricate the 55 chain. The other end of the shaft 20, which projects from the chamber 18, is provided with a pulley 28 adapted to receive the belt 8 for driving the well rig.

60 Mounted on the end of the shaft 20 beyond the sprocket 24 is a sleeve 29. This sleeve is secured by means of a bolt 30 to the end of the shaft and fixed against movement by means of a dowel 31 or other suitable fastening. The outer end of the sleeve 29 is provided with a radial flange 32. A flywheel 33

65

is loosely mounted so as to turn freely on the sleeve 29 and is held in place by the flange 32. The sleeve 29 provides a bearing on which the fly wheel may turn, and lubricating means, such as the oil cup 34, may be provided to insure lubrication of this bearing. The flywheel 33 may also be fixed so as to rotate with the shaft 20. This may be done by means of a series of bolts 35 or other suitable means for detachably connecting the flywheel to the hub of the sprocket 24 or to the shaft itself. The construction shown in Figure 2 is a simple one, since the flywheel may be easily detached by removing the bolts 35. 75

In the use of this device, the power unit is mounted on a suitable foundation as shown in Figure 1, and the pulley 28 is belted to the band wheel 7. If pumping operations are being carried out, the flywheel is fixed to rotate with the shaft 20 by inserting the bolts 35. Under these conditions, the flywheel will take up fluctuations of load due to any unbalancing of the pump rod load, and consequently the load on the motor may be held practically constant. It will be noted, furthermore, that the flywheel takes up fluctuations at the shaft 20 and thereby relieves the chain 25 as well as the motor of a fluctuating load. When hoisting operations are to be carried out, the bolts 35 may be removed so that the flywheel will turn freely on the shaft 20. The motor may now be driven forward or backward and started or stopped as rapidly as desired, without being hindered by the weight of the flywheel. In this way rapid hoisting operations can be carried out and braking can be accomplished by reversing the motor which is free to apply its full braking effect to stopping the load on the rig. During such operation, the flywheel remains practically stationary and the shaft 20 turns within it, the sleeve 29 providing a bearing which may be kept lubricated as described. It will also be noted that this device provides a speed reducing unit which is compact and self-contained and which may be applied to any well rig.

It is obvious that various changes may be made, within the scope of the appended claim, in the details of construction without departing from the spirit of this invention; it is, therefore, to be understood that this invention is not limited to the specific details shown and described. 115

Having thus described the invention, what 120 is claimed is:

A power unit for oil wells, comprising, a motor, a driving wheel thereon, a countershaft, a driven wheel on one end of said countershaft, driving connections between said wheels, a flywheel free on said countershaft adjacent said driven wheel, a second driving wheel on the other end of said countershaft, a driven shaft having a driven wheel thereon, driving connections between 125 130

said second driving and driven wheels, the hub of said first driven wheel being projected and having a radially extending flange on said projection, and releasable driving connections between said flywheel and said flange independent of said countershaft.

5 In testimony whereof I affix my signature this 6th day of October, 1927.
